UNITED STATES PATENT OFFICE.

HAZAEEL B. POWELL, OF NAPOLEON, OHIO.

IMPROVEMENT IN HAND-HOLDS FOR REINS.

Specification forming part of Letters Patent No. **222,947**, dated December 23, 1879; application filed November 3, 1879.

To all whom it may concern:

Be it known that I, HAZAEEL B. POWELL, of Napoleon, in the county of Henry and State of Ohio, have invented a new and Improved Hand-Hold for Reins, of which the following is a specification.

The object of my invention is to provide a strong, durable, and easily-adjusted hand-hold for driving-reins.

The invention consists of a metal hand-hold composed of a buckle for attaching said hand-hold to the reins and a plate projecting from one side of the buckle, which is designed to be clasped between the thumb and forefinger.

In the accompanying drawings, Figure 1 is a perspective view of the hand-hold and rein, showing the manner in which they are grasped by the hand. Fig. 2 is a top view of the hand-hold. Fig. 3 is a longitudinal section of the same, and Fig. 4 is a cross-section thereof.

Similar letters of reference indicate corresponding parts.

Referring to the drawings, A is the frame of the buckle, and B is the swiveled tongue. From the front side, *a*, of the frame A projects a concave plate, C. D represents one driving-rein.

The manner of applying and using the hand-hold is as follows: The plate C is turned par-

allel to the rein and toward the animal's head; the tongue B is swung up so as to leave the buckle open; the rein is now doubled into a loop, with the upper side out, at the proper distance from the bit, and the loop is thrust from the under side of the holder up through the buckle sufficiently to allow the tongue B to be shut down under the loop, in the manner shown in Figs. 1 and 3.

In driving, the rein forward of the buckle is clasped between the first and second fingers, and the plate C is clasped between the forefinger and thumb, in the manner shown in Fig. 1.

This hand-hold is economical, easily applied and adjusted, and furnishes a strong hold for the hands on the reins.

Having thus described my invention, I claim as new and desire to secure by Letters Patent—

As an improved article of manufacture, the herein-described hand-hold for driving-reins, composed of frame A, tongue B, and concave plate C, as and for the purpose substantially as described.

HAZAEEL B. POWELL.
